CLAIM

(57) I claim the ornamental design for the cheese knife, as shown and described.

DESCRIPTION

FIG. 1 is a perspective view of the cheese knife, showing my new design.

FIG. 2 is a front view of the cheese knife.

FIG. 3 is a back view of the cheese knife.

FIG. 4 is a top view of the cheese knife.

FIG. 5 is a bottom view of the cheese knife.

FIG. 6 is a right side view of the cheese knife; and,

FIG. 7 is a left side view of the cheese knife.

A hang hole visible in FIGS. 1-3 is illustrated in phantom lines and forms no part of the claimed invention.
